Application January 26, 1938, Serial No. 186,981

4 Claims. (Cl. 178—5.6)

My invention relates to improvements in methods and systems for television communication.

In the more successful methods and systems proposed heretofore for television communication, and employing a cathode-ray pick-up tube at the transmitter and a cathode-ray viewing tube at the receiver, it has been required that there be at each station two circuits for deflecting the scanning ray at the line and field frequencies, respectively. Also, it has been required that line and field pulses be transmitted on the same carrier wave as the video signals, and these pulses have been used at the receiver for synchronization. In these prior methods and systems, not only has difficulty been encountered in holding the deflecting circuits at the receiver locked in step with those at the transmitter, but a substantial portion of the transmitted energy has been expended in transmitting the synchronizing pulses.

With the foregoing in mind, it is one of the objects of my invention to provide an improved method and system for television communication employing cathode-ray tubes at both stations, and in which no synchronizing pulses are required to be transmitted to the receiver, and in which either the deflection circuit at the line frequency or both deflection circuits at the line and field frequencies, respectively, can be omitted at the receiver.

Another object of my invention resides in the provision of an improved method and system for television communication which has advantages over those proposed heretofore in the way of greater simplicity of construction and manner of operation, and higher efficiency.

Other objects and advantages will hereinafter appear.

In accordance with my invention, the voltage waves at the respective line and field frequencies are generated at the transmitter and transmitted either over wire or radio to the receiver. These same waves are applied to the deflection plates or coils of the pick-up tube at the transmitter and the viewing tube at the receiver, so that the electron ray in the tubes must of necessity be always in step during the scanning action. When a common power supply at a given frequency of 60 cycles, for example, is available, only the voltage wave at the line frequency is transmitted, and voltage waves at the field frequency are generated locally at the two stations and locked in step by the common power supply. Because of the impossibility of this system getting out of synchronization as to both line and frame fre-

quencies, a much higher interlace ratio is possible. This allows a given detail picture to be transmitted over a much narrower frequency band, thereby allowing more transmitters to operate in a given frequency band. Likewise, the transmission of much higher definition pictures over the same frequency band can also be accomplished.

Another advantage of this system is that it will receive pictures of transmitters operating at any desired line and frame frequencies. With the present systems it is necessary that all transmitters operate with exactly the same respective scanning frequencies if all receivers are to be capable of receiving from any one of the transmitters.

My invention resides in the improved method and system of the character hereinafter described and claimed.

For the purpose of illustrating my invention, an embodiment thereof is shown in the drawings, wherein

Figures 1 and 1a are simplified, diagrammatic views of a television transmitting station and a television receiving station, respectively, constructed and operating in accordance with my invention;

Figs. 2 and 2a are views similar to Figs. 1 and 1a, respectively, showing a modification;

Figs. 3 and 3a are views similar to Figs. 2 and 2a, respectively, showing another modification;

Figs. 4 and 4a are simplified views, in block diagram, of a complete television system operating in accordance with my invention;

Figs. 5 and 5a are views similar to Figs. 4 and 4a, showing a modification;

Fig. 6 is a schematic view showing an interlaced pattern possible to obtain with my improved method and system; and

Fig. 7 is a detail, elevational view of a part which may be used in connection with my invention.

With reference to Fig. 1, the numeral 10 designates a scanning device in the form of a cathode-ray pick-up tube of any suitable, conventional construction, and comprising a photosensitive screen 11 and an electron gun for developing a ray 12 of electrons directed at and focused on the adjacent surface of the screen.

In operation, a light image of the view or object 13 for transmission is projected by a lens system 14 onto the photosensitive screen 11, and the electron ray 12 is deflected horizontally at a suitable line-frequency by the plates 15 and is simultaneously deflected vertically at a suitable field 16

frequency by the plates 16 so that the screen 11 is scanned.

Since the specific form of construction of the pick-up tube 10 does not have any important bearing on my invention, and since the principle and manner of operation of cathode-ray pick-up tubes of the general type shown are well known to those skilled in the art, no detail explanation is believed to be necessary. The picture or video signals developed by the tube 10 may be taken from a collector electrode 17, fed to an amplifier tube 18, and thence transmitted over a line 19 to the receiving station.

At the transmitting station are deflecting circuits common with respect to the pick-up tube 10 and the cathode-ray receiver tube 20 at the receiving station. One of these circuits comprises a gas-discharge tube 21 and an amplifier tube 22, and generates a saw-tooth voltage wave at the desired field frequency. In operation, the condenser 23 is charged at a uniform rate until the plate of tube 21 reaches a potential whereat ionization takes place to cause practically instantaneous discharge of this condenser. Resistances 24, 25 and 26 are used to regulate the frequency of the saw-tooth voltage wave generated, and a cathode-bias resistor 27 is effective to regulate the amplitude of the voltage wave. The saw-tooth voltage wave is applied to the amplifier tube 30 22 through a coupling condenser 28 and an input resistance 29. The reference numerals 30 and 31 designate, respectively, a cathode-bias resistance and a plate resistance for the tube 22.

The amplified saw-tooth voltage wave at the field frequency is fed through a coupling condenser 32 to the transmission line 33. This voltage wave is impressed across the deflecting plates 15 through ground and a connection 34 from the line 33. Also, this same voltage wave is impressed across the corresponding deflecting plates 15a of the receiver tube 20 through ground and a connection 34a from the transmission line 33.

The construction and principle of operation of the scanning device or cathode-ray tube 20 at the receiving station are similar to that of the transmitter tube 10, the main difference residing in the fact that the screen of the receiver or viewing tube 20 is a fluorescent screen 11a which may be formed on the inside surface of the end wall of this tube.

The deflecting circuit for generating a saw-tooth voltage wave at the desired line frequency comprises a gas-discharge tube 35 and an amplifier tube 36. This circuit is the same as the frame-deflection circuit except that the capacity of the condenser 37 is smaller than that of the corresponding condenser 23 since the frequency of the voltage wave generated is higher. The amplified saw-tooth voltage wave at the line frequency is fed through a coupling condenser 38 to the transmission line 39, from whence it is impressed across the deflecting plates 16 through ground and a connection 40 from the line 39. Also, this same voltage wave is impressed across the corresponding deflecting plates 16a of the receiver tube 20 through ground and a connection 40a from the transmission line 39.

At the receiving station, a connection 41 from the transmission line 19 applies the amplified picture or video signals to the control grid or electrode 42 of the electron gun in the tube 20, whereby the intensity of the ray 12a of electrons is modulated or made to vary in accordance with the lights and shadows at the respective ele-

mental areas of the object 13 being televised. Since the electron rays 12 and 12a are scanning the respective screens 11 and 11a in exactly the same manner and in synchronism, a visible image of the object 13 will be produced on the 5 fluorescent screen 11a.

At the transmitting station, a transformer 43 supplies the necessary heater voltages, and also has high voltage windings for the rectifier tubes 44 and 45. The rectifier tube 44 supplies voltage 10 to the amplifier tubes 18, 22 and 36 and the gas-discharge tubes 21 and 35. The rectifier tube 45 supplies the necessary voltages for the pick-up tube 10.

Condensers 46, 47, 48 and 49 are filter condensers, and 50 designates a filter choke. Resistances 51, 52, 53 and 54 are bleeder resistances for rectifier tube 44, and resistances 55, 56, 57, 58 and 59 form the bleeder for rectifier tube 45.

When the two deflecting circuits are properly locked in at the respective desired frequencies, a resistance 60 may be used to provide coupling between these circuits.

If it is desired to have and maintain the line frequency an even multiple of the field frequency, this may be accomplished by a connection 61 and a coupling condenser 62 between the plate of the amplifier tube 36 operating at line frequency and the grid of the gas-discharge tube operating at the field frequency. Otherwise, this 30 connection and condenser are omitted.

Resistances 63 and 64 are connected across the bleeder and allow for positioning of the beam pattern on the photosensitive screen 11. Resistances 65 and 66 connect the position controls to 35 the deflection plates, as shown.

The condensers 67, 68, 69 and 70 are by-pass condensers.

The picture or video signals taken from the collector electrode 17 are fed to the amplifier tube 40 18 through a coupling condenser 71 and an input resistance 72. A resistance 73 supplies plate voltage to the tube 18, and a resistance 74 applies the proper voltage to the collector electrode 17.

When the distance between stations is great, or in cases where the signals are transmitted at low level, amplifiers may be used locally at the receiving station, and supplied respectively from the connections 34a, 40a and 41 to amplify the 50 two saw-tooth voltages and the incoming video signals to sufficient levels.

At the transmitter, a screen of the secondary-emissive type may be used in lieu of a photosensitive screen.

For the purpose of transmitting sound simultaneously with the picture, a microphone 75 and amplifier 76 are provided at the transmitter, the sound signals being sent over an independent transmission line 77 to a loudspeaker 78 at the 60 receiving station.

At the receiver, a transformer 79 supplies any necessary heater voltages, and also high voltage to a rectifier tube 80. The proper voltages are supplied to the receiver tube 20 by the circuit 65 shown, comprising filter condensers 81 and 82, bleeder resistances 83, 84, 85 and 86, and a by-pass condenser 87. The correct bias is applied to the control or modulating electrode 42 by a resistance 88, and the video signals are applied 70 to this electrode through a coupling condenser 89.

In the system shown in Figs. 2 and 2a, the construction and manner of operation of the pick-up and viewing tubes are the same as in Figs. 1 and 1a.

Also, with the following exceptions, the two systems are the same, and for simplicity of comparison, corresponding parts and connections in the two systems have been designated by the same respective reference characters.

In Figs. 2 and 2a there is the common line-deflection circuit at the transmitting station, comprising the gas-discharge tube 35 and the amplifier tube 36, for generating and amplifying the saw-tooth voltage wave at the line frequency, this wave being impressed across the deflection plates 16 of the pick-up tube 10 and transmitted as before over the line 39 and connection 40a and impressed across the deflection plates 16a of the viewing tube 20. However, the receiving station has its own field-deflection circuit comprising a gas-discharge tube 21a and an amplifier tube 22a corresponding to and operating in the same manner as the tubes 21 and 22, respectively, in Fig. 2.

That is, in Fig. 2, the tubes 21 and 22 operate as in Fig. 1 to generate a saw-tooth voltage wave at the field frequency which is impressed across deflection plates 15 by the line 33 and connection 34, but the wave is not transmitted as in Fig. 1. At the receiver, the tubes 21a and 22a operate to generate a saw-tooth voltage wave at the field frequency which is impressed across deflection plates 15a by the line 33a.

For the purpose of maintaining operation of the two field-deflection circuits at the respective stations at the same desired field frequency, a common and local source of 60-cycle alternating current 90 is utilized. As shown, the 60-cycle wave is applied to the grid of both gas-discharge tubes 21 and 21a.

In Fig. 2a there is, in addition, the rectifier tube 91 and associated bleeder circuit for supplying voltage to the tubes 21a and 22a.

In the system shown in Figs. 3 and 3a, the construction and manner of operation of the pick-up and viewing tubes are the same as in Figs. 1, 1a, 2 and 2a.

Also, with the following exceptions, the system in Figs. 3 and 3a is the same as that in Figs. 2 and 2a, and for simplicity of comparison, corresponding parts and connections in these two systems have been designated by the same reference characters. In Fig. 3, the saw-tooth voltage wave at the field frequency is generated by a half-wave rectifier tube 92 and the associated filter arrangement comprising a filter condenser 93 and the resistance 94 connected across this condenser. With each positive half-cycle of the 60-cycle power frequency, the condenser 93 is charged, and this charge leaks out by way of the resistance 94, thereby generating a 60-cycle saw-tooth voltage wave with a somewhat longer return trace than by the method in Figs. 1 and 2. In the systems described, this is not objectionable because there is effective scanning during the return trace as well as during the initial trace.

In Fig. 3a, the difference over Fig. 2a resides also in the deflecting circuit for generating the saw-tooth voltage wave at the field frequency. That is, as in Fig. 3, a half-wave rectifier 92a and a filter condenser 93a and resistance 94a are used for this purpose.

In the transmitting station shown in Fig. 4, the output from the cathode-ray pick-up tube 95 is fed through a preamplifier 96 and a main amplifier 97 to the transmitter 98. A generator 99 operates to develop the saw-tooth voltage wave at line frequency which is fed to the sound am-

plifier 100 and transmitter 101, whereby this wave is transmitted on the sound carrier. A generator 102 operates to develop a saw-tooth voltage wave at the field frequency of 60 cycles, and is held at this frequency by a local 60-cycle power supply 103.

From the foregoing it will be understood that in Fig. 4 the video signals are transmitted on one carrier wave and the saw-tooth voltage wave for deflecting the cathode-ray at line frequency is transmitted with the sound signals on the sound carrier wave.

At the receiving station, shown in Fig. 4a, the signals are amplified by a radio-frequency amplifier 104. A locally generated oscillation is mixed with the signals, as represented, and fed to the video intermediate-frequency amplifier 105 and the audio intermediate-frequency amplifier 106. The video signals are then demodulated, amplified, and applied to the control grid 20 of the viewing tube 107 to modulate the intensity of the electron ray.

The audio signals and the saw-tooth voltage wave at line frequency being on a different carrier wave, do not interfere with the video signals, and are separated and pass through their own intermediate-frequency amplifier 106 and are then demodulated. The voltage wave passes through a selective filter 108, and after being amplified by an amplifier 109 is impressed across the deflection plates of the viewing tube 107 to cause deflection of the electron ray at the line frequency.

The sound signals are amplified by an amplifier 110 and fed to the loudspeaker 111.

As in Figs. 2a and 3a, a local generator 113 operates to develop the saw-tooth voltage wave at the field frequency, and is held at this frequency by the local 60-cycle power supply 114 common to both stations, as in Figs. 2, 2a and Figs. 3, 3a.

In Figs. 5 and 5a no sound is transmitted, and both saw-tooth waves, at the line and field frequencies respectively, are transmitted on the sound carrier. That is, at the transmitter, the outputs from both deflection circuits 99 and 102 are fed to the audio amplifier 100 and then pass to the transmitter 101 for transmission on the sound carrier, as represented in Fig. 5. The operation, otherwise, is the same as in Fig. 4. At the receiver, no local field generator, such as the generator 113 in Fig. 4a, is necessary, since the saw-tooth voltage wave at the field frequency is received from the transmitter, along with the saw-tooth voltage wave at the line frequency. These waves are demodulated, and separated by the respective filters 108 and 116, and then amplified by the respective amplifiers 109 and 117 before being impressed across the deflection plates.

In cases where a secondary-emissive screen is used at any of the transmitting stations in lieu of a photosensitive screen, one method for this purpose might be to employ an aluminum plate with letters, numerals, or any desired figure or view printed, with a carbon ink, on the surface to be scanned. As the printed surface is scanned by the electron ray, the voltage output is different when the ray is directed at the aluminum surface than when it is directed at the carbon printing, whereby the picture signals are developed in accordance with the printing scanned by the electron ray. It will be understood that in this method different transmitter tubes are required for different messages, since the message transmitted from any one tube is fixed by the

particular carbon printing on the aluminum plate. However, if for example letters of the alphabet are printed on the aluminum plate and arranged in some such manner as in Fig. 7, and at the transmitter the electron ray is positioned so that it scans only one letter or figure at a time and under control of the operator, only such letter or figure will appear on the fluorescent screen of the viewing tube. In this way, messages can be sent, such as by spelling out code words.

Code messages can also be transmitted by using a conventional type of viewing tube at the receiving station and placing in front of the fluorescent screen a transparent card with the letters of the alphabet thereon and arranged in some such manner as in Fig. 7. At the transmitter, no picture signals are developed, but only the two saw-tooth voltage waves at the respective line and field frequencies are transmitted to the receiver, as in Figs. 1 and 1a and Figs. 5 and 5a. By controlling the relation of these waves at the transmitter, the scanned area at the viewing tube can be positioned or selected to embrace any one letter or numeral on the card.

By actually transmitting to the receiver the saw-tooth wave at the line frequency, and either transmitting also the saw-tooth wave at the field frequency or using local field generators at the two stations synchronized by a common power supply of a given frequency, as explained, it follows that the two electron rays will always scan the respective screens in the same manner and in synchronism. For this reason, it is possible in my improved system and method to obtain the advantage of using line and field frequencies to give an interlace ratio greater than 2, and even as high as 4.

For example, in the various systems used heretofore, in which cathode-ray tubes are employed at both stations, and line and field impulses are transmitted for synchronization, some success has been had in obtaining an interlace ratio of 2. But even at this lowest interlace ratio, the line and field impulses sometimes fail to hold the interlaced pattern at the viewing tube.

Assuming a line frequency of 6615 and a field frequency of 60 in my improved system, as shown in Figs. 1 to 5a, there will be 110.25 lines per field, and accordingly a frame frequency of 15 and an interlace ratio of 4. That is, at each station, and with reference to Fig. 6, the electron ray during the first field of any one frame will scan the effective screen area ABCD along the solid lines 1 to 110.25. During the second field of this frame, the electron rays will scan the dot lines 111 to 220.50. During the third field of this frame, the electron rays will scan the dash lines 221 to 330.75. During the fourth field of this frame, the electron rays will scan the dash-dot lines 331 to 441, and then be at the initial starting point for the next frame of four fields.

From all the foregoing it will be seen that in my improved method and system, practically one hundred percent of the transmitted energy for the video signals is used for the same, since the saw-tooth voltage wave or waves are transmitted on the sound carrier. Also, no synchronizing pulses are required, and when both voltage waves are transmitted no deflection circuits are required at the receiver. When there is available a common power supply at a given frequency such as 60 cycles, it is only necessary to transmit the saw-tooth wave at the line frequency since the saw-tooth voltage wave at the line frequency can

be generated locally at the two stations in a number of different ways and must of necessity be in step. Any difference in phase at the two stations can be readily corrected for by a suitable phase-shifting arrangement.

In the specification and claims, the following meaning is intended for the various terms used. A frame is a single complete picture. Frame frequency is the number of times per second the frame or entire effective screen area is completely scanned in interlaced scanning. Field frequency is the number of times per second the frame or entire effective screen area is fractionally scanned in interlaced scanning. The interlace ratio is the ratio of field frequency to frame frequency. For other definitions, reference may be made to the publication Electronics, issue of August, 1937.

It will be understood that various embodiments of my invention other than those disclosed, are possible without departing from the spirit of my invention or the scope of the claims.

I claim as my invention:

1. In the art of simultaneous television and sound communication between two stations wherein cathode-ray tubes are utilized at the respective stations for scanning, the method of operation which comprises transmitting from one of said stations to the other station picture signals on a carrier wave and simultaneously transmitting sound signals on another carrier wave, developing a continuous electrical wave at a line frequency for deflecting the scanning ray at said first-named station at said line frequency, transmitting said continuous electrical wave on the sound-carrier to said other station from said first-named station, demodulating at said other station to obtain thereat said electrical wave, and utilizing the electrical wave so obtained to deflect the scanning ray at said other station at said line frequency.

2. In the art of simultaneous television and sound communication between two stations wherein from one of said stations to the other station picture signals are transmitted on a carrier wave and sound signals are simultaneously transmitted on another carrier wave, the method of operation which comprises utilizing a ray-deflecting wave to control scanning action at said first-named station, transmitting said ray-deflecting wave on the sound carrier to said other station from said first-named station, demodulating at said other station to reproduce thereat said ray-reflecting wave, and utilizing the ray-deflecting wave so obtained at said other station to control scanning action at said other station.

3. In the art of simultaneous television and sound communication between two stations wherein cathode-ray tubes are utilized at the respective stations for scanning, the method of operation which comprises transmitting from one of said stations to the other station picture signals on a carrier wave and sound signals simultaneously on another carrier wave, utilizing a ray-deflecting wave to cause deflection at a given line frequency of the scanning ray at said first-named station, transmitting said ray-deflecting wave on the sound carrier to said other station from said first-named station, demodulating at said other station to reproduce thereat said ray-deflecting wave, and utilizing the ray-deflecting wave so obtained at said other station to cause deflection at said line frequency of the scanning ray at said other station.

4. In a system for television communication between two stations, scanning devices in the

- form of cathode-ray tubes located respectively at said stations, means common with respect to said tubes and located at one of said stations and operating to develop a continuous electrical wave
- 5 5 at a given line frequency, means for reproducing said continuous electrical wave at the other station, means associated with the cathode-ray tube at said first-named station and having impressed thereon said electrical wave and operating to deflect the scanning ray at said line frequency, a deflecting circuit associated with the cathode-ray tube at said other station for reflecting the scanning ray at said field frequency, a source of alternating-current common with respect to and local to said stations, and connections between said common source of alternating-current and said deflecting circuits for maintaining operating action of each of the latter at said field frequency.
- 10 10 10 means associated with the cathode-ray tube at said other station and having impressed thereon said electrical wave and operating to deflect the scanning ray at said line frequency, a deflecting circuit associated with the cathode-ray tube at said first-named station for reflecting the scanning ray at said field frequency, a source of alternating-current common with respect to and local to said stations, and connections between said common source of alternating-current and said deflecting circuits for maintaining operating action of each of the latter at said field frequency.
